Specification for Design.

Patented Dec. 10, 1918.

Application filed July 23, 1917. Serial No. 182,353. Term of patent 14 years.

To all whom it may concern:

Be it known that I, WALTER H. HENDRICKSON, a citizen of the United States, residing at Chicago, in the county of Cook and State of Illinois, have invented a new, original, and ornamental Design for a Fire-Extinguisher, of which the following is a specification, reference being had to the accompanying drawing, forming part thereof.

Figure 1 is a side elevation of a fire extinguisher showing my new design and Fig. 2 is a perspective of the same.

I claim:

The ornamental design for a fire extinguisher, as shown.

WALTER H. HENDRICKSON.
